UNITED STATES PATENT OFFICE.

GEORGE EMMETT WITT, OF FRESNO, CALIFORNIA.

CRUDE-OIL BURNER.

SPECIFICATION forming part of Letters Patent No. 698,938, dated February 25, 1902.

Application filed September 23, 1901. Serial No. 76,268. (No model.)

To all whom it may concern:

Be it known that I, GEORGE EMMETT WITT, a citizen of the United States, residing at Fresno, in the county of Fresno and State of California, have invented a new and useful Crude-Oil Burner, of which the following is a specification.

My invention is an improved burner especially adapted for burning crude oil in steam or other furnaces; and it consists in the peculiar construction and combination of devices hereinafter fully set forth and claimed.

In the accompanying drawings, Figure 1 is partly an elevation and partly a sectional view of a crude-oil burner embodying my improvements. Fig. 2 is a transverse sectional view of the same, taken on a plane indicated by the line *a a* of Fig. 1. Fig. 3 is a similar view taken on a plane indicated by the line *b b* of Fig. 1.

To an inlet-chamber 1, which is here shown as a T-coupling, is coupled an oil-feed pipe 2, which is provided with a valve 3 to cut off or control the flow of oil to the inlet-chamber.

25 A steam-pipe 4, which leads from a boiler or other source of steam, is provided with an injector-nozzle 5, which enters and extends in the inlet-chamber through nearly the entire length of the latter and past the inner 30 end of the oil-feed pipe 2. The said injector-nozzle is of less diameter than the interior diameter of the inlet-chamber, so that a space is formed in the latter for oil around the injector-nozzle. The said steam-feed pipe 4 is

35 provided with a valve 6 to control the supply of steam to the burner. A mixing-chamber 7, which is here shown as a perforated tube, leads from the inlet-chamber, the diameter of the said mixing-chamber being preferably

40 less than that of the inlet-chamber. The outer end of the mixing-chamber is here shown as closed by a plug 8, which is provided in its sides with channels 9. An atomizing jacket or chamber 10, which is here 45 shown as a tube, surrounds the mixing-chamber and contains the latter, and the said tubular atomizing-jacket is here shown as coupled directly to the inlet-chamber. An annular space is formed in the tubular atomizing-jacket around the perforated tubular

50 mixing-chamber. A jet-tip 11 extends from the outer end of the atomizing-jacket and is

here shown as coupled thereto, as at 12. In practice the burner is disposed in or adapted to discharge into the furnace, and the latter 55 is provided with the usual or any suitable means for supplying it with air and for creating a draft therethrough to promote and maintain combustion therein.

In the operation of my improved crude-oil 60 burner the valve 6 is first opened to cause steam to be admitted thereto through the pipe 4 and injector-nozzle 5, and the latter, together with the other parts of the burner, become heated by the steam. The oil-valve 3 is then 65 opened to cause the oil to be fed to the inlet-chamber 1. The oil strikes against the heated injector-nozzle and the interior of the inlet-chamber and is heated therein and thereby to such an extent as to cause it to flow 70 freely. The oil passes from the inlet-chamber into the mixing jacket or chamber, where it is subjected to the action of the jet or blast 75 of steam from the injector-nozzle, the oil and steam becoming commingled in the mixing-chamber 7, and the pressure and force of the steam causing the oil, which is commingled therewith, to be discharged through the perforations in the mixing-chamber into the atomizing-chamber. The impact of the oil 80 against the atomizing-chamber, together with the action of the steam, atomizes the oil, reducing it in the presence of the steam with which it is commingled to infinitesimal globules, which, together with the steam, are dis- 85 charged into the furnace through the jet-tip 11, the channels 9 of the plug 8 permitting the commingled steam and atomized oil to flow freely from the atomizing-jacket to the jet-tip. The said plug 8 centers the tubular 90 mixing-chamber in the atomizing-jacket. The oil being thus atomized and commingled with steam burns readily in the furnace without smoke and in a flame of great intensity. The action of the steam in passing through 95 the parts of the burner keeps the latter clear, so that the burner never becomes clogged with the oil and never requires to be cleaned. When the valves which regulate the admission of the oil and steam to the burner have been once properly adjusted, the burner requires practically no further attention.

Having thus described my invention, I claim—

1. In a crude-oil burner, the combination of an inlet-chamber, an oil-feed pipe communicating therewith, a steam-pipe having an injector-nozzle extending into said inlet-chamber, a tubular perforated mixing-chamber leading from the inlet-chamber, and an atomizing-chamber inclosing said mixing-chamber and into which the latter discharges, substantially as described.
- 10 2. In a crude-oil burner, the combination of an inlet-chamber, means to supply oil and steam thereto, a perforated mixing-chamber into which said inlet-chamber discharges, and an atomizing-chamber inclosing said mixing-chamber, and into which the latter discharges, substantially as described.
- 15 3. In a crude-oil burner, the combination

of an inlet-chamber to which steam and oil are supplied, a perforated tubular mixing-chamber extending from said inlet-chamber, 20 an atomizing-chamber, inclosing said mixing-chamber, and a plug in the outer end of the latter, to center the same in the atomizing-chamber, said plug being channeled for the discharge of commingled steam and atomized 25 oil from the atomizing-chamber, substantially as described.

In testimony that I claim the foregoing as my own I have hereto affixed my signature in the presence of two witnesses.

GEORGE EMMETT WITT.
